UNITED STATES PATENT OFFICE

92,627

DESIGN FOR A WEIGHING MACHINE CASING

David W. Rochestie, Trenton, N. J.

Application April 16, 1934, Serial No. 51,426

Term of patent 3½ years

To all whom it may concern:

Be it known, that DAVID W. ROCHESTIE, a citizen of the United States, residing at Trenton, in the county of Mercer and State of New Jersey, has invented a new, original and ornamental Design for a Weighing Machine Casing, of which the following is a specification, reference being had to the accompanying drawing forming part

thereof, wherein the figure shows a perspective view of the weighing machine casing.

I claim:

The ornamental design for a weighing machine casing as shown.

In testimony whereof, I affix my signature.

DAVID W. ROCHESTIE.
